WALL TYPE CAN OPENER

George A. Lehmann, Ferguson, Mo., assignor to The Dazey Corporation, St. Louis, Mo., a corporation of Missouri

Application May 23, 1956, Serial No. 41,613

Term of patent 14 years

(Cl. D22—2)

FIG. 1.

FIG. 2.

FIG. 3.

FIG. 4.

Fig. 1 is a top plan view of a wall type can opener embodying my new design;

Fig. 2 is an elevational view showing one side of the said can opener;

Fig. 3 is an elevational view showing the other side of said can opener, and

Fig. 4 is a front end view of the can opener.

I claim:

The ornamental design for a wall type can opener, substantially as shown.
